(57) CLAIM

The ornamental designs for a flosser device, as shown and described herein.

DESCRIPTION

FIG. 1 is a front, top, right side perspective view of a flosser device in accordance with an embodiment of the present design.

FIG. 2 is a front view of the flosser device shown in FIG. 1. FIG. 3 is a rear view of the flosser device shown in FIG. 1. FIG. 4 is a left side plan view of the flosser device shown in FIG. 1.

FIG. 5 is a right side plan view of the flosser device shown in FIG. 1.

FIG. 6 is a top side plan view of the flosser device shown in FIG. 1; and,

FIG. 7 is a bottom side plan view of the flosser device shown in FIG. 1.

In the drawings, the shading shows contours and the broken lines are for illustrative purposes and form no part of the claimed design.
